UNITED STATES PATENT OFFICE.

CLARE H. DRAPER, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

LOOM.

Application filed March 17, 1921. Serial No. 453,077.

To all whom it may concern:

Be it known that I, CLARE H. DRAPER, a citizen of the United States, residing at Hopedale, in the county of Worcester and 5 State of Massachusetts, have invented certain new and useful Improvements in Looms; and I do hereby declare the following to be a full, clear, and exact description of the invention, such as will enable others 10 skilled in the art to which it appertains to make and use the same.

The present invention relates to an improvement in looms.

Heretofore in the operation of a loom the 15 cloth stands fast at the breast beam and is only taken up there as it is advanced by the beat of the lay, as a consequence of which owing to the shedding operations the length of the warp from the fell to the whip roll 20 is lengthened and shortened at each shedding operation. This is compensated for by mounting the whip roll so as to yieldingly 25 resist the pull of the warp exerted by the shedding operation. Therefore the warps advance and retreat slightly through the 30 drop wires and harnesses, thus sawing or reaving back and forth as a result of which they are worn more or less, sometimes to the extent of seriously weakening them and facilitating or causing breakage.

The object of the present invention is to produce a loom having means for automatically taking up and letting out the cloth after it is woven near or at the breast beam 35 so as to reduce the amount of reaving or sawing through the drop wires and harnesses.

The invention consists in the loom hereinafter described and particularly defined in 40 the claims.

In the accompanying drawings illustrating the preferred form of the invention Fig. 1 is a longitudinal, sectional, diagrammatic elevation of a loom; Fig. 2 is a plan of the 45 warp beam and associated parts; and Fig. 3 is a sectional elevation of a cloth take-up and let-out device on a larger scale than that shown in Fig. 1 for the purpose of more clearly illustrating the construction.

The illustrated embodiment of the invention 50 is described as follows: From the warp beam 1 the warp extends up over the whip roll 2, yieldingly supported in operative position by the spring 3 in the usual manner,

Thence the warps extend through the drop 55 wires 4 of the warp stop motion and over and under lease rods 5 and 6 to the heddles or harnesses 7 and 8, thence through the reed 9 of the lay 10 to the fell from which the cloth extends to the draw roll 11 and to the 60 wind-up roll 12 at the front of the machine.

Just in the rear of the breast beam 13 is mounted the cloth take-up and let-out device 65 which consists generally of a channel bar arranged concave side up, over the edges of 65 which the cloth extends. Centrally disposed above the open side of the channel is a yieldingly supported take-up bar which rises and falls as the tension on the cloth is increased and decreased by the formation of 70 the sheds.

In detail this cloth take-up and let-out device is described as follows: A supporting bar 20 bolted at 21 at its ends to the breast beam is provided which extends rearwardly, 75 downwardly and transversely across the loom under the cloth. This bar 20 may conveniently be termed the cloth take-up and let-out supporting bar or the channel support. To this bar 20 is attached a channel 80 bar 22 which is secured to the bar 20 at each end by bolts 23 which are screwed into the cross bar 20 and down on the bottom of the channel bar 22 so as thereby to hold the channel bar rigidly in position, its upper 85 edges engaging the under surface of the cloth as it approaches the draw roll or breast beam, as the case may be. These bolts 23 extend upwardly some distance and carry the take-up bar 24, said take-up bar being 90 provided with two holes adapted to loosely receive the bolts 23. Each bolt 23 is embraced by a spring 25 which engages the take-up bar at its lower end and a washer 95 at its upper end, which latter forms an abutment for the spring and is secured in place by a nut 26. The pressure of the springs 25 on the take-up bar 24 is such as to depress the cloth slightly between the edges of the channel bar 22 and thereby bend the cloth 100 or deflect it out of its normal position, that is out of a straight path from the fell to the draw roll.

The operation of this loom in so far as it is modified by the presence of this cloth take-up device is as follows: Assuming the 105 position of the parts as shown in Fig. 1 with a shed formed for the passage of the

shuttle from one side of the loom to the other, the tension on the cloth induced by the draw roll supports the take-up bar in such position that the pressure of the cloth 5 against the bar equals the pressure exerted upon the bar by the weight of the bar and the pressure of the springs exerted thereon. Now as the heddles move past each other in opposite directions to form a new shed 10 they thereby lengthen the distance from the fell to the lease and this permits the fell to move toward the draw roll under the influence of the pressure of the take-up bar exerted on the cloth, which take-up bar 15 moves downward slightly into the channel bar 22 and thereby takes up a portion of the increased length of warp between the fell and the lease at the warp beam, thereby diminishing the amount of reeving or sawing 20 of the warps through the eyes of the thread supports, i. e., the harnesses and drop wires. As the heddles pass each other to form the new shed they again exert a pull upon the warps and pull the fell rear- 25 wardly in the machine, thereby lifting again the take-up bar and causing it to give up the cloth which it had taken up in its downward movement.

It is apparent that a considerable part of 30 the reeving or sawing of the warps through the harnesses and drop wires is eliminated by this construction with the important result of diminished wear upon the warps, due to such reeving and sawing, is accomplished.

35 The particular form of take-up and let-out device applied to the cloth at the breast beam to take-up cloth as the shed closes and give up cloth as the shed again opens is immaterial to my invention viewed in its 40 broader aspects, which contemplates broadly providing the loom at the breast beam with means for taking up cloth as the shed closes

and giving up cloth as the shed opens so as thereby to reduce the reeving and sawing of the warps through the harnesses and drop 45 wires.

Having thus described the invention, what is claimed is:

1. A loom having, in combination, a breast beam, a lay, heddles and drop wires, 50 and a cloth take-up and let-out consisting of three members, two of which engage one side of the cloth near the breast beam and the third of which engages the cloth between the first two, and means for yieldingly pressing the members toward the cloth so as thereby to take up cloth when the shed is closed and give up cloth as the shed is opened.

2. A loom having, in combination, a 60 breast beam, a lay, heddles and drop wires, and a cloth take-up and let-out consisting of a channel bar supported with its edges in contact with one surface of the cloth, a take-up bar supported with its surface in 65 engagement with the opposite surface of the cloth between the edges of the channel bar, and springs for yieldingly pressing the channel bar and take-up bar toward each other to take up cloth as the heddles close 70 and give up cloth as the heddles open.

3. A loom having, in combination, a breast beam, a lay, heddles and drop wires, and a cloth take-up and let-out device supported in position in the rear of the breast beam comprising a channel bar having its edges in engagement with the under surface of the cloth, a take-up bar having a portion engaging the upper side of the cloth between the edges of the channel bar, and springs 80 for yieldingly pressing the take-up bar against the cloth.

CLARE H. DRAPER.
